POWER OPERATING MECHANISM FOR TYPEWRITERS

Application filed July 27, 1925. Serial No. 46,461.

The invention relates to typewriters, book-keeping or billing machines and the like and has among its objects to provide power means for shifting the machine.

In billing machines such as are now in common use it is necessary for the operator to manually shift the typewriter, or head as it is commonly called, in order to clear the platen preparatory to receiving the ledger sheet and bill. Such manual operation is necessary after each bill is printed and since the head is very heavy the repeated shifting of the head causes fatigue of the operator.

Our invention provides power means for shifting the head which may be readily attached to the machines now in common use. The invention permits quick and easy operation of the billing machines calling upon very little of the operator's strength with the result that the operator will not become fatigued as in the use of the ordinary machine. It is ordinarily necessary to train an operator for several months before he is able to operate the ordinary billing machine and because of the shifting operation of the head an operator cannot usually operate a machine for a longer period of time than a few years, after which time he must be relieved by a new operator. This is manifestly an expensive procedure. With our invention the fatiguing operations of the machine are power actuated with the result that the length of service of an operator is not restricted because of any fatiguing effect incident to operating the machine.

A further object of the invention is to provide power means for actuating the under carriage of the machine whereby the carriage is rapidly and smoothly accelerated. Provision is also made to quickly and without shock to the machine, absorb the inertia so as to bring the machine to a standstill at the proper place. The invention also includes power means for actuating the head carriage whereby it is moved to the proper position and brought to rest without injurious shock to the machine. Means is further provided for pneumatically actuating the carriages of the machine including means for varying the point of cut-off of the fluid being supplied

to the motor whereby the most efficient operation of the machine may be obtained and shock eliminated.

The figures we have described show the application of our invention to one commercial form of billing machine. It is however to be understood that it is equally applicable to many other machines, such as typewriters, bookkeeping machines, and others using carriages which must be moved periodically during operation.

With these and other objects in view, the invention resides in the novel features of construction and combination and arrangements of parts as more fully hereinafter described and claimed.

Referring to the drawings:—

Figure 12 is a plan thereof;

Figure 12^a is an end view thereof at the valve end;

Figure 13 is an end elevation thereof at the opposite end;

Figure 14 is a perspective view of the tripping mechanism.

In the drawings 10 indicates a typewriter or head supported by rollers 11 which engage tracks 12 of the carriage 13. The latter carriage is slidably supported by rollers 14 which engage the tracks 15 of the bed 16.

The bed 16 may be fixedly supported by a table 17'. The bed 16 is formed with the horizontal platen 17 for accommodating a ledger sheet which may be mounted at its opposite longitudinal edges on the projections 18 carried by an endless carrier 19, the projections 18 passing through appropriately spaced openings of the ledger sheet (not shown). The carrier 19 passes around end rollers 20 rotatably actuatable by the member 21 to position the ledger sheet longitudinally forwardly or rearwardly of the machine in the customary manner. The typewriter is provided with the usual operating keys 22. The rear rollers 14 of the carriage, as best shown in Figure 2, are mounted to rotate with the axle 23 upon which is also mounted the brake drum 24, the latter always rotating with the axle 23. 25 is a brake band having a braking surface cooperating with the brake drum 24 so that when the brake band is held fixed or is prevented from rotating with the drum, a braking effect is produced which prevents rotation of the rear rollers 14 and consequently stops the movement of the carriage 13 longitudinally of the bed 16. For so holding the brake band 25 stationary the latter is provided with a peripherally knurled or serrated portion 26 engaged by a pawl 27 adapted to be lowered into engagement with the knurled portion 26 of the brake band or raised free of engagement therewith upon rotation of the brake rocker rod 28. Rotation of the brake rod to apply the brake may be effected by pressing downwardly on the control 29, which operates to press downwardly on a rod 28' (see Fig. 6). The rod 28' is connected at its ends by links 28^a with the brake rocker rod 28, so that downward movement of the rod 28' rotates the rod 28 through links 28^a sufficiently to release the brake. Our invention provides means for automatically controlling the action of the brake as hereinafter described. Ordinarily a spring 30 coiled about the brake rod 28 serves to maintain the pawl 27 in engagement with the brake band so as to prevent movement of the carriage 13 without first releasing the brake. All of the foregoing described parts are of the usual construction or may be of any other preferred construction.

In operation of the machine as thus far described, to clear the platen 17 preparatory to inserting a ledger sheet or other paper to receive printing of the typewriter, the operator presses downwardly on the control 29 which rocks the brake rocker rod 28 to release pawl 27 from engagement with the knurled portion 26 of the brake drum 25, thus leaving the carriage 13 free from braking action. The operator then pushes on the head 10 to move the same and the carriage 13 rearwardly until the carriage clears the platen 17, the rollers 14 at the front and rear of the carriage rolling on the tracks 15 of the

bed 16. At the same time, or previously or thereafter, the head 10 is moved to one side (according to the travel of the typewriter), such as to the left, against the action of the coil spring 30'. The latter spring may be of usual construction and acts upon the spool housing 31 to tend to wind thereon the steel tape 32, one end of which is attached to the typewriter. The spool 31 is rotatably carried by a bracket 33 fixed to the carriage 13. The platen 17 is now cleared to receive the ledger sheet, above which is usually placed the bill with a sheet of carbon paper in between. The ledger sheet may be perforated along its longitudinal edges to receive the projections 18.

The operator then presses downwardly on control 29 to release the brake and pulls forwardly the head 10 and carriage 13 to bring the typewriter above the platen and sufficiently forward to suit the reach of the operator so that he can best operate the keys 22. If the proper operating position of the typewriter is not such as to align the printed type with the proper line of the ledger sheet, then it is understood that the ledger sheet may be adjusted either forwardly or backwardly by reason of the member 21 and the endless carrier 19. Ordinarily each operator places the successive ledger sheets on the platen so that the proper line, to receive the type, is the same distance back from the front marginal edge of the platen, whereby the head is pulled forwardly to the same point each time. However, the head 10 may be pulled forwardly to any desired position above the platen and the ledger sheet and bills or other papers to be printed may be moved longitudinally of the platen, backwardly and forwardly to any desired position.

After the typewriter has been pulled forwardly to the proper position, the operator actuates the keys 22 to print the desired characters on the bills, ledger sheet, etc., the head 10 advancing transversely of the platen to the right, as the keys are selectively operated, the head being moved under the influence of the tape 32 and spring 30' in the customary manner. After printing one or more lines on the ledger sheet the head 10 and carriage 13 are then pushed rearwardly and the head moved to the left against the action of the spring 30', to clear the platen for receiving the next bill whereupon the above operations are repeated.

From the foregoing description it is apparent that the operator must move the head and carriage many times a day as the platen must be cleared after each bill is printed by the typewriter. The movement of the head and carriage forwardly over the platen calls only for a natural movement of the body, and while our invention is equally adapted to actuate the machine in this direction by power it is not deemed necessary with the

type of machine illustrated. The fatigue of the operator is caused by the necessity to quickly and repeatedly push the head and carriage to the rear and at the same time 5 or after the rearward movement of these parts, to move the head to the left to restore the parts to their initial position. In short, it is the clearing of the platen which is a strain on the operator and our invention is 10 therefore directed to provide power means for automatically moving the head and carriage rearwardly and laterally.

Our invention thus includes power means for simultaneously moving the head to the 15 rear and to the left, or to its initial position. Furthermore, the parts are quickly accelerated and quickly decelerated without any injurious shock to the delicate mechanism of the typewriter and other parts of the machine. 20 It is in the furtherance of these and other objects that our invention comprises the following mechanism:

Supported at opposite sides of the bed 16 are the main cylinders 34 and 35 respectively. 25 The cylinder 34 is shown best in Figures 2, 5, 6 and 7 and comprises the supporting brackets 36, 37, fixed to the bed 16. Within the cylinder is a piston 38 connected preferably through a loose universal-like joint with a piston rod 39, the loose joint permitting a limited amount of relative movement between the parts. Adjacent the front end of cylinder 34 is a valve cylinder 40, the cylinders communicating by the port 41. 42 indicates a supply pipe for fluid under pressure, such as compressed air, the fluid passing on its way to the valve cylinder 40 through the throttling valve 43, the latter controlling the 30 rate of flow of the fluid from a suitable supply to the valve cylinder. For controlling the passage of fluid from the valve cylinder through port 41 to the cylinder 34, the valve 44 is provided and is adapted to be reciprocated by a valve rod 45 having its opposite 35 end slidably supported by the bracket 46. The valve rod 45 is provided with a key 45^a engageable in bracket 36, whereby rotation of the valve rod is prevented. Thus, the notches 66, referred to hereinafter, are kept 40 facing downwardly in their proper position, as will presently be apparent. 42^a indicates the exhaust port communicating with the valve cylinder. In the position shown in Figure 5 the piston cylinder is open to the 45 exhaust by way of the port 41, exhaust port 42^a and the exhaust pipe 42^b. A port 42^c is also provided in the cylinder 34, said port communicating with a pipe 42^d leading to cylinder 35. Port 42^e is indirectly controlled 50 by the valve 44 to admit fluid to cylinder 35 and also to exhaust cylinder 35 by way of port 41 and thence through the pipe 42^b. The valve rod 45 carries a collar 47 adjustable thereon by set-screw 48. 49 is a valve actuating cross rod, rotatably supported in bearing

brackets 50, said rod having at one end the yoke 51 bearing against the collar 47 for actuating the valve rod 45. Rigidly secured to the side of the bed 16 is a bar 52 having a plurality of spaced notches 53 along its lower 70 edge. Slidably mounted on said bar is a bell-crank lever clip 54 upon which is pivotally mounted upon the pivot pin 55 the bell-crank lever 56 provided with a roller 57 engageable by a cam 57^a secured to the carriage 13 and 75 having an inclined under surface 57^b for engagement with the roller 57 as the carriage 13 is moved rearwardly. The clip 54 is provided with a stop mechanism for positioning it at any of the notches 53, this mechanism comprising a latch 58 connected by a pin 59 with a control button 60, the latch being normally urged upwardly to engage the notches by a spring 61. A check-pin 62 limits the movement of the bell-crank lever in one direction, the other end of the lever bearing against a bell-crank lever stop 63 having a 80 latch 64 actuatable by a button 65 in a similar manner with the button 60, whereby the stop 63 may be positioned at various points along the valve rod 45, the latter having for purposes of engagement by the latch 64 a plurality of notches 66 relatively spaced to correspond with the notches 53.

The rear end 39^c of the piston rod 39 bears 85 against a spring 67 housed within the bushing 68, the other end of the spring bearing against an adjustable member 69 threaded within the bushing 68 and actuatable by the nut 70, whereby the compression of the spring 67 90 may be regulated. The spring 66 keeps the end 39^c of the piston rod in spaced relation with the member 69 until fluid is admitted to the piston cylinder. The bushing 68 carries the nuts 71, between which is clamped the 95 angle bar 72, which bar is secured to the carriage 13 for actuating the same. 73 is a collar adjustable along the piston rod 39 by set-screw 74, the collar bearing against the downwardly bent part 75 of the brake slide rod 76, 100 the part 75 being formed with the opening 77 for slidably receiving the piston rod. The 105 brake slide rod 76 slides in the bearings 78 and is formed with a hook-shaped portion 79 for receiving one end of the bell-crank lever 110 80 pivoted to rock in the fixed bearing 81.

The forward part of the lever 80 may pass through the frame of the machine to afford a second bearing (not shown). The other end 115 80' of the bell crank lever 80 is connected 120 through a link 82 with a lever 83 clamped at 84 with the brake rocker rod 28. The lever 83 may also receive the rod 28' (see Figures 5 and 6).

On the other side of the machine, or right side as the parts are arranged for purpose of illustration, it is preferable to provide a second cylinder 35 which operates simultaneously with the cylinder 34 to equalize or balance the thrust imparted to the carriage 13 125

and thus prevent any tendency to twist the carriage as it is moved. The cylinder 35 is provided with a piston 85, as before, and a piston rod 86. As before stated, the valve 44 of the valve cylinder 40 serves to admit fluid simultaneously to act on the piston 38 and also through the exhaust and inlet pipe 42¹ to act on the piston 85. When the valve 44 exhausts the cylinder 34 it also exhausts cylinder 35 through the pipe 42¹ as aforesaid. The piston rod 86 is connected to operate the angle rod 87 which is secured to the carriage 13.

For moving the head 10 transversely of the platen 17 to restore the typewriter to its initial position, the following mechanism is provided: Suitably secured along the rear of the carriage 13 is a cylinder 88, the securing means as shown comprising any suitable clamping brackets as 89 and 90, respectively embracing the cylinder and being secured conveniently to parts of the carriage as to the uprights 91 and 92 respectively, the brackets being best shown in Figures 4 and 11. The cylinder 88 has a valve cylinder 93 within which is a valve 94 for controlling the supply of fluid from the intake pipe 95. 96 is the inlet port and 97 is the passage between the valve cylinder 93 and the cylinder 88. When the valve 94 is moved to the right, as viewed in Figure 11, the cylinder 88 exhausts through the passage 97, port 98 and exhaust pipe 99. As before, the inlet 95 is preferably controlled by a throttle valve 100 whereby the rate of flow of the fluid supplied therethrough may be readily controlled. The pipes 95 and 99 are preferably formed of flexible tubing to permit unrestricted movement of the cylinder 88 and the carriage. If desired, the source of compressed air may be in the form of a pressure tank (not shown) secured below the table 17' and to which the supply pipes 42 and 95 lead. A slot 101 may be cut through the table to accommodate the pipes 95 and 99 and permit their movement in accordance with the travel of the carriage 13.

Within the cylinder 88 is a piston 102 operative through a piston rod 103 to move the angle bar 104, one end of which is secured at 105 to the rear face of the head 10, and the other end of which is bent at 106 to engage the piston rod 103, the clamping nuts 107 maintaining the parts in engaged relation. Operatively connected with the valve 94 is the valve rod 108 which has a splined supporting engagement intermediate its length, at 109, with an extension 110 of the bracket 89. The end of the valve rod is provided with a plurality of spaced notches 111 selectively engaged by the valve rod stop 112 which is constructed like the stop 63, having a spring controlled latch 113 operated by a control button 114. Connected with the stop 112 a sleeve 115 is mounted slidably with the stop

112 on the valve rod. 116 indicates a collar adjustably mounted on sleeve 115 by a set-screw 121. The collar 116 is adapted to be engaged by the valve tripping bracket 117. The latter bracket is fastened to the bar 104 and has a bifurcated part 118 which straddles the valve rod 108. As the head 10 moves to the right as viewed in Figure 11, the bifurcated part of the valve tripping bracket strikes the collar 116 to move the valve rod to the right to actuate the valve 94, thereby cutting off the supply of fluid to the cylinder 35 and exhausting the same. The upper end 119 of the arm 120 loosely encircles the sleeve 115, as shown in Figure 12. The lower end 80² of the arm 120 is secured to the head-stop 122, which is adjustable along the carriage bar 123, the latter having a plurality of notches 124 spaced correspondingly with the spacing of notches 111. The stop 122 is provided with a spring-controlled latch 125 engageable with the notches 124 and controlled by the button 126.

By reason of the set-screw 121 the collar 116 may be adjusted on the sleeve 115 to prevent movement of the valve rod 108 sufficiently to cause the valve 94 to strike the end of the wall. Thus, by properly positioning the collar 116, the bracket 117 will engage the collar and move the same to the right (as viewed in Fig. 12), the head 10 engaging stop 122 (and hence preventing further movement of the valve rod) before the valve 94 has been moved into engagement with the end wall of the valve cylinder. 100

Depending from the bracket 89 is an arm 127 forming a pivotal bearing 128 for the bell-crank lever 129. One end of the latter lever is connected with the downwardly extending rod 130 terminating in the hook portion 131. The other end of the bell-crank is bifurcated at 135 to straddle the valve rod 108 and is adapted to operatively engage a valve collar 132, the latter being adjustable along the valve rod by the set-screw 133. 116 Preferably a spring 134 normally retains the bell-crank 129 and the rod 130 in the position shown in Figure 11.

As shown in Figure 4 the rod 130 extends downwardly between the bifurcated parts of 115 a guide bracket 136 which is secured to the under face of the angle rod 87. The hook portion 131 as shown in Figure 11 is adapted to have sliding engagement with an actuating bar 137 as shown in Figure 1 whereby the latter bar can pull downwardly on the rod 130 at any position of the hook portion 131 along the bar 137. The bar 137 is supported adjacent its opposite ends by the rock arms 138, the latter arms being mounted upon the rod 139 rotatable in bearing brackets 140 secured to the bed 13 of the machine. 125

As shown in Figure 4 the valve actuating cross rod 49 extends transversely across the rear of the machine, one end of the rod actu- 130

ating the valve rod 45 as described above, and the other end being bent at 141 (see Figure 8). 142 is a link connecting the bent end 141 with the actuating bar 137 so that when the cross rod 49 is given a partial rotation by the actuating mechanism to be described the bent end 141 will swing the actuating bar 137 by reason of the link 142. Swinging of the bar 137 will cause the rod 130 to be pulled downwardly, thereby actuating the valve rod 115 as hereafter described. Preferably, a spring 143 as shown in Figure 10 is coiled about the cross rod 49 to restore the same to its initial position after being actuated. For actuating the cross rod 49 any suitable tripping mechanism may be provided. Preferably the cross rod is provided with a lever 144 to which a cable 145 is connected, the other end of the cable extending to a suitable hand or foot actuating mechanism. The latter mechanism is preferably pedal operated, the cable 145 extending downwardly at the rear of the machine to a point convenient for operation. In Figure 14 the cable 145 is shown connected to an actuating bell-crank lever 146 pivoted at 147 to a fixed support 148, and provided with an end 149 adapted to be actuated by the foot of the operator to effect the movement of the carriage and typewriter. The bell-crank may have a bent portion 150 carrying the adjustable pin 151 adapted to engage a fixed bracket 152 for limiting the swing of the bell-crank. A spring 153 serves to restore the bell-crank after being actuated to pull the cable 145.

In operation, after the carriage and typewriter have been moved forwardly manually into proper position above the platen 17, to act upon the ledger sheet, bills, etc., which have previously been placed on the platen, the keys 22 of the typewriter are actuated in the customary manner to print the desired characters on the ledger sheet, bills, etc. The operation thus far is that customarily pursued and involves little exertion on the part of the operator and no fatiguing exertion as referred to before. When the operator desires to clear the platen by returning the carriage 13 to the rear of the machine, and also to move the typewriter or head 10 to the side of the machine, as to the left as viewed in Figure 1, the operator trips the end 149 of the bell-crank lever 146, with his foot, thus pulling on the cable 145. The latter cable rocks the valve actuating cross rod 49, by reason of the lever 144, the cross rod actuating the controlling valves for the various cylinders as follows: One end of the cross rod moves the valve rod 45 to the left, as viewed in Figure 5, by the engagement of the yoke 51 with the collar 47. Movement of the valve rod simultaneously throws the roller 57 upwardly, by reason of the stop 63 acting on the bell-crank lever 56, and also moves the valve 44 to the left, permitting the compressed fluid to flow

from the valve cylinder 40 past the ports 41 and 42^a, the latter leading to cylinder 35 and the former to the cylinder 34. The fluid then acts on the piston 38 to cause the latter to move to the left as shown in Figure 5. The first movement of the piston rod 39 causes the collar 73 to move the brake slide rod 76 to the left, thereby acting through the bell-crank 80 and link 82 to rock the brake rocker rod 28 against the action of spring 30 and release the brake band 25 from engagement with the pawl 27. The carriage 13 is then free from the braking action. Upon continued movement of the piston rod 39, the part 75 of the slide rod 76 engages the nuts 80 71. During the aforesaid movement of the piston rod, the spring 67 is compressed within the bushing 68, the spring not being strong enough to move the bushing and angle bar 72 and yet being of sufficient strength to return the piston rod and piston when the latter is not being subjected to the air pressure, the purpose of which will be presently apparent. Further movement of the piston rod causes the angle bar 72 to be moved rearwardly of the machine or to the left as viewed in Figure 5, carrying with it the carriage 13 and the head 10 mounted thereon. The carriage continues to move until the cam surface 57^b engages the roller 57, whereby the valve rod 45 is moved to the right to actuate the valve 44 to cut off the supply of fluid to the piston 38 and at the same time to exhaust the cylinder 34. The cylinder 35 on the other side of the machine is at the same time exhausted through the pipe 42^a, ports 41 and 42^a and the pipe 42^b. As soon as the air pressure is relieved in the cylinder 34 the spring 67 acts to move the collar 73 and piston rod 39 forward, thereby permitting the spring 30 to freely act as it moves the slide rod 76 and rocks the brake rocker rod 28 to engage the pawl 27 with the serrated portion 26 of the brake band 25, whereby the latter is held stationary, thus producing braking with the brake drum 24. Since the brake drum 24 is mounted on the axle 23 carrying the carriage rollers 14, braking of the drum 24 causes the carriage to stop its rearward movement. It should be understood that the cylinders 34 and 35 act simultaneously, being controlled by the single valve 44. The thrust rearwardly on the carriage is thus equalized at opposite sides, preventing any tendency to twist the carriage during the power stroke. For stopping the carriage at any point desired, the button 60 is actuated to move the clip 54 at any point along the bar 52, corresponding to one of the notches 53. Thus, the position of the roller 57 is varied to effect cut-off at any desired point with respect to the travel of the carriage 13. After the clip 54 has been adjusted to the desired position, the stop 63 is likewise adjusted to a corresponding position along the valve rod 45. 130

By regulating the throttle valve 43, the speed of travel of the carriage 13 may be controlled. Since the carriage and the head thereon is very massive, it will be apparent that it is desirable to apply a large initial force to produce quick acceleration of the carriage and thereafter to apply sufficient force to maintain a speedy movement of the carriage. The large initial force must, however, be such that it will not produce an injurious shock to the rather delicate parts of the typewriter and machine in general. After the carriage is brought up to its travelling speed a further problem is presented in quickly absorbing the energy of inertia to bring the carriage to rest without shock to the machine. Our invention satisfactorily meets all of the aforementioned difficulties, affording speedy movement and stopping of the carriage without injurious shock. By reason of the throttle valve 43, when the valve 44 is actuated to supply the compressed fluid to the cylinders 34 and 35, the full pressure of the fluid will act against the pistons 38 and 85. Thus, the carriage is rapidly accelerated. Thereafter, however, the throttling effect of the valve 43 prevents such continued high pressure against the pistons since the latter are travelling longitudinally of their respective cylinders at such a rate as to effect a throttling action of the incoming fluid. Thus, by regulating the valve 43, the speed of travel of the carriage may be regulated, at the same time affording full fluid pressure at the initial movement of the carriage. As aforesaid, the point of cut off and exhaust may also be varied to determine the point at which the carriage brake is to be applied. The latter brake quickly brings the carriage to rest without any shock to the machine parts.

At the same time that the cross rod 49 actuates the valve rod 45, it also swings the bar 137 downwardly, by reason of the link 142 actuated by the bent end 141 of the cross rod. The downward movement of bar 137 carries with it the rod 130, engagement between these parts being effected by the hook 131. The rod 130 acts through the bell-crank 129 to rock the latter to cause the bifurcated portion 135 to move against the valve collar 132, thereby moving the valve rod 108 and valve 94 to the left as viewed in Figure 11. Movement of the valve brings ports 96 and 97 into communication, thus supplying air from the pipe 95 to the cylinder 88 to act upon the piston 102. The latter is thereby caused to move transversely of the machine or to the right, as viewed in Figure 11, the piston rod 103 acting on the bent end 106 of bar 104 to move the head 10 transversely of the movement of the carriage 13 against the increasing resistance of the spring 30'. When the bell-crank 129 moves the valve rod 108 to actuate the valve, the movement of the valve rod is limited by the stop 112 striking the

end 119 of arm 120. As the head 10 nears the end of its stroke, the bracket 117 engages the collar 116 and moves the latter and the sleeve 115, together with the stop 112, until the head 10 strikes the head stop 122, thus causing the valve rod 108 to be returned to its initial cut-off position, the collar 116 permitting adjustment to prevent the valve from striking against the end wall of the valve cylinder as aforesaid. The cylinder 88 is thus exhausted through the port 98 and pipe 99. The limiting position of the head is determined by striking against the stop 122. By adjusting the stops 122 and 112 along the bar 123 and the valve rod 108 respectively, the typewriter or head 10 may be brought to rest at any desired point transversely of the platen 17 or the carriage 13.

Since it is desirable to clear the platen 17 as quickly as possible after each operation so that the operator can place the next ledger, bill, etc., in place, it is desirable to move the carriage 13 rearwardly at a relatively high speed. However, it is not essential that the head 10 be restored to initial position in the same period of time since, the operator will be engaged for a brief period replacing the ledger sheets, etc., on the platen after the carriage has cleared the same. Therefore, we preferably throttle down the pressure of the fluid introduced to the cylinder 88 by reason of the throttle valve 100. This valve may be so regulated that the period of time occupied in restoring the head will overlap that required to move the carriage rearwardly by an amount substantially equal to or less than the time required by the operator to change the ledger sheets, etc. Thus, a slow moving power mechanism is provided for the typewriter, which though not essential, is desirable to avoid shocks in starting and stopping the same. Furthermore, it will be noted that the restoring movement of the typewriter is against the action of the spring 30' the resistance of which is increased as the typewriter is moved transversely of the carriage by the power mechanism. This effects a tendency to slow down the velocity of the typewriter during its final movement which further prevents any tendency to jar the typewriter when it is brought to rest against the stop 122.

The carriage 13 and head 10 being automatically restored to their initial positions, the foregoing cycle may be repeated.

Preferably, the roller 11 to the left of the typewriter, as viewed in Figure 1, is provided with a guard shield 11^a affording protection against contact with the fingers of the operator. The right front roller 11 is protected by the proximity of the machine frame 11^b.

It will be noted that we have provided motor or power actuated means for moving the carriage and also the typewriter. Our

invention further includes means for quickly accelerating the carriage and speedily stopping the same at variable points without shock or jar to the machine. Further, motor or power means is provided for relatively slowly moving the typewriter or head against an increasing resistance.

By reason of the throttle valves controlling the fluid inlet to each of the cylinders, means is provided for varying the speed of travel of the carriage and head. The throttle valves also afford an initial high force to be applied to the piston, followed by a lesser force as the piston travels along the cylinder.

It should be understood that instead of restoring the carriage and the typewriter to their initial position, if desired, our mechanism could be arranged to actuate the parts from the initial position to their operative position. Essentially our invention is directed to power or motor actuated mechanism for relieving the operator from undue fatigue in the operation of machines of the character described. Instead of a typewriter being employed as shown, it is obvious that our invention is equally applicable to other intelligence reproducing mechanisms.

While it is believed that from the foregoing description, the nature and advantage of our invention will be readily understood, we desire to have it understood that we do not limit ourselves to what is herein shown and described and that such changes may be resorted to when desired as fall within the scope of the claims.

What we claim as our invention is:—

1. In combination with a machine of the character described comprising a platen, a carriage movable longitudinally over the platen between variable limits, a printing machine carried by the carriage and movable transversely thereof between variable limits, of mechanism for applying power to quickly accelerate and move the carriage over the platen between said limits, and means for moving the printing machine transversely thereof, and a single control member for actuating the carriage and printing machine moving means.

2. In combination with a machine of the character described comprising a platen, a carriage movable longitudinally over the platen between variable limits, a printing machine carried by the carriage and movable transversely thereof, of mechanism for applying power to simultaneously move the carriage longitudinally of the platen and the printing machine transversely thereof.

3. A machine of the character described, comprising a platen, a carriage movable longitudinally of the platen between variable limits, a printing machine carried by the carriage and movable transversely thereof, said carriage adapted to be manually moved for-

wardly of the platen to selective positions, a cylinder fixed relative to said platen and extending transversely to the travel of the printing machine, a piston operative in said cylinder and connected to move the carriage, and means adapted to be operated when the carriage is in said forward positions for admitting fluid to said cylinder to act on said piston for restoring the carriage to a position rearwardly of the platen.

4. In a machine of the character described, the combination with a table, a carriage movable thereover between variable limits and a printing machine mounted on said carriage, the combined weight of the printing machine and carriage being relatively great, of means for applying power to quickly move the carriage selectively between said limits, and energy-absorbing means for decelerating and stopping the carriage after a predetermined travel of the carriage, and means for varying the speed of travel of the carriage, said last-named means always affording substantially the same initial force for initially quickly accelerating the carriage.

5. A machine of the character described comprising a platen, a carriage movable longitudinally of the platen between variable limits, said carriage adapted to be manually moved forwardly of the platen to selective positions, said carriage provided with a brake for checking movement of the carriage, said brake adapted to be manually released when the carriage is moved forwardly, and means for applying power to move the carriage from said forward position to a position rearwardly of the platen, said power means first acting to release said brake.

6. A machine of the character described comprising a platen, a carriage movable longitudinally of the platen between variable limits, said carriage adapted to be manually moved forwardly of the platen to selective positions, said carriage provided with a brake for checking movement of the carriage, said brake adapted to be manually released when the carriage is moved forwardly, means for applying power to move the carriage from said forward position to a position rearwardly of the platen, said power means first acting to release said brake, and means for automatically applying the brake after a predetermined rearward movement of the carriage.

7. A machine of the character described comprising a platen, a carriage movable longitudinally of the platen between variable limits, said carriage adapted to be manually moved forwardly of the platen to selective positions, said carriage provided with a brake for checking movement of the carriage, said brake adapted to be manually released when the carriage is moved forwardly, and means for applying power to move the carriage from said forward position to a position rearwardly of the platen, said power means first

- acting to release said brake, means for stopping the application of power to said carriage after a predetermined movement thereof, and means for thereafter automatically applying the brake to bring the carriage to rest.
8. In a machine of the character described comprising a platen, a carriage movable longitudinally of the platen between variable limits, a printing machine mounted on said carriage, a cylinder fixed relative to the platen, a piston operable in the cylinder and connected to move the carriage, a source of fluid under pressure, a valve controlling the operation of the piston, a valve rod, said carriage and printing machine carried thereby adapted to be manually moved forwardly of the platen to a plurality of selective positions, means operative in any of said forward positions of the carriage for actuating the valve rod to admit fluid to act on the piston whereby the carriage is moved rearwardly of the platen to clear the same.
9. In a machine of the character described comprising a platen, a carriage movable longitudinally of the platen between variable limits, a printing machine mounted on said carriage, a cylinder fixed relative to the platen, a piston operable in the cylinder and connected to move the carriage, a source of fluid under pressure, a valve controlling the operation of the piston, a valve rod, said carriage and printing machine carried thereby adapted to be manually moved forwardly of the platen to a plurality of selective positions, means operative in any of said forward positions of the carriage for actuating the valve rod to admit fluid to act on the piston whereby the carriage is moved rearwardly of the platen, and means acting on said valve rod after a predetermined position of said carriage for actuating the valve rod to exhaust the cylinder.
10. In a machine of the character described comprising a platen, a carriage movable longitudinally of the platen between variable limits, a cylinder fixed relative to the platen, a piston operable in the cylinder and connected to move the carriage, a source of fluid under pressure, a valve controlling the operation of the piston, a valve rod, said carriage adapted to be manually moved forwardly of the platen to a plurality of selective positions, means operative in any of said forward positions of the carriage for actuating the valve rod to admit fluid to act on the piston whereby the carriage is moved rearwardly of the platen, means acting on said valve rod after a predetermined position of said carriage for actuating the valve rod to exhaust the cylinder, a brake for said carriage, and means for automatically applying the brake to bring the carriage to rest, said braking means being active after the cylinder has been exhausted.

11. A machine of the character described comprising a platen, a carriage movable thereover, a typewriter movable transversely of the carriage and carried thereby, a cylinder carried by the carriage, a piston operatively associated with the cylinder and connected to move the typewriter in one direction, a valve controlling the action of the piston, a valve rod, means for tripping the valve rod to cause movement of the typewriter, and means operative after a predetermined movement of the typewriter for actuating the valve rod to exhaust the cylinder.

12. In a machine of the class described, the combination with a platen, a carriage movable thereover, and printing mechanism movable on the carriage, of means for applying power to simultaneously move the carriage and printing mechanism, and means for predetermined the relative speed of movement of said carriage and printing mechanism.

13. In a machine of the class described, the combination with a platen, a carriage movable thereover, and a printing mechanism movable on the carriage, of mechanism for applying power to move the carriage and printing mechanism and including separate controls for predetermined the relative speed of movement of said carriage and printing mechanism, respectively.

In testimony whereof we affix our signatures.
